[57] CLAIM

The ornamental design for a multiform printer, as
shown and described.

DESCRIPTION

FIG. 1 is a front elevational view of a multiform printer
showing my new design;

FIG. 2 is a left side elevational view thereof;

FIG. 3 is a top plan view thereof;

FIG. 4 is a rear elevational view thereof;

FIG. 5 is a top, front and right side perspective view
thereof;

FIG. 6 is a left side elevational view of a second em-
bodiment of the multiform printer shown in FIG. 1;

FIG. 7 is a top plan view of FIG. 6;

FIG. 8 is a rear elevational view of FIG. 6; and

FIG. 9 is a top, front and right side perspective view of
FIG. 6.

FIG. 3

FIG. 1

FIG. 2

FIG. 4

FIG. 5

FIG. 7

FIG. 6

FIG. 8

FIG. 9
